SILENCER

Robert L. Nulty, Detroit, Mich.

Application June 17, 1935, Serial No. 26,993

1 Claim. (Cl. 137—160)

This application relates to silencers and more particularly aims to provide a silencer of the resonating type.

The silencer here shown is characterized by 5 the provision of spaced groups of holes in the inner and intermediate ones of the three shells used, which hole grouping and spacing has been found to give desirable operating characteristics to the silencer whereby the same silencer may 10 be used on six cylinder engines and eight cylinder engines interchangeably and without sacrifice of efficiency.

For an understanding of the silencer here disclosed, reference should be had to the appended 15 drawing, whose

Fig. 1 is a longitudinal section view of the silencer.

Referring to the drawing, it will be seen that 20 the silencer there shown is of the straight through type wherein exhaust gases course through an innermost shell 10 without interruption from the inlet to the outlet thereof, there being an expansion chamber 11 formed at the outlet end of the silencer. Diaphragms 12 connect and 25 space the inner shell 10 with respect to the intermediate shell 14 and an annular resonator chamber 15 spaces the intermediate shell 14 from the outermost shell 16.

In the construction shown, six diaphragms 12 30 are used, though this number may be varied as found desirable. For purposes of convenience the six diaphragms here shown are numbered 1-6 and it is observed that the innermost shell is provided with a multiplicity of fine holes between the inlet end header 17 and diaphragm 1, between diaphragms 2 and 3, and between

diaphragms 4 and 5; the portions of the innermost shell between diaphragms 1 and 2, 3 and 4, and 5 and 6 are not so perforated. The intermediate shell is provided with a multiplicity of fine extruded holes arranged in groups with 5 the first group being adjacent the inlet header 17, the second and third groups adjacent diaphragm 2, the fourth and fifth groups being adjacent diaphragms 4, and the sixth group being adjacent diaphragm 6. The remaining portions 10 of the intermediate shell are left unperforated.

Due to the hole spacing and grouping shown, the silencer here shown operates satisfactorily and efficiently whether it be used on a six cylinder engine or upon an eight cylinder engine. 15

Now having described the silencer here shown, reference will be had to the claim which follows for a determination of the scope of the invention.

I claim:

A silencer including three relatively telescoped 20 transversely spaced shells, inlet and outlet end headers closing the inlet and outlet ends of these shells, three or more longitudinally spaced diaphragms between the headers and connecting and spacing the innermost shell with respect to 25 the intermediate shell, groups of holes on the innermost shell adjacent and on the silencer inlet sides of alternate ones of these diaphragms, said innermost shell being otherwise imperforate, a group of holes on the intermediate shell adja- 30 cent and on the outlet side of the inlet header, groups of holes on the intermediate shell adjacent and on opposite sides of each diaphragm other than those mentioned as the alternate diaphragms. 35
